UNITED STATES PATENT OFFICE.

KARL SCHOENEMANN, OF MANNHEIM-RHEINAU, GERMANY.

PROCESS OF WORKING DOWN THE PRODUCTS ARISING WHEN COAL IS LIQUEFIED BY HYDROGENATION.

No Drawing. Application filed December 1, 1926, Serial No. 152,067, and in Germany December 11, 1925.

The oils arising when coal is liquefied by being heated under hydrogen that is subjected to high pressure (berginization) still contain considerable amounts of solid substances, viz, the inorganic components of the coal and a certain amount of the coal itself. The oils contain also a comparatively large percentage of asphalt, and there arise difficulties when the solid substances are to be separated from the reaction products. The products may be worked down, as usually, by distillation, it is true, and this can be effected, with a suitable manner of operation, without detriment to the oils, but it is unavoidable that also a considerable amount of asphalt arises which contains the solid, insoluble substances, and the value of which is, therefore, greatly diminished. The main amount of the liquid substances may be separated from the solid ones also by filtration or with the aid of a centrifugal machine, but a material amount of semi-soft asphalt still remains with the solid substances and, besides, the operation of these methods in a practical manner is connected with certain difficulties as regards apparatus.

I have discovered that the working down of the products mentioned can be carried through in a very practical manner by adding a relatively small amount of an aliphatic hydrocarbon or of aliphatic hydrocarbons, for instance gas oil, to the coal oil products that have been freed from their light components, as well as from water. It is possible when working with a suitable temperature, to separate the solid, insoluble substances together with the asphalt in a very simple manner, and the surplus oils can be separated from the deposit merely by decanting, and be worked down further.

This precipitation process can also be carried through in such a manner that first the insoluble solid substances are precipitated together with a comparatively small amount of asphalt, whereas the main amount of the asphalt remains suspended or dissolved in the oil present above the precipitated solid substances. The insoluble components can be separated, together with a small quantity of asphalt from the liquid present above the precipitated substances, by decanting, and the remaining asphalt will then separate and precipitate from that liquid when left standing then during a certain time in a state in which it is perfectly free from solid components

and can again be separated by decanting from the asphalt-less oil present above it. The temperature conditions requisite for this fractional separation and precipitation are different according to the condition of the oils. A practical example is given farther below.

The separation of the small amounts of the precipitation oil remaining in the asphalt can be easily attained, for instance, by means of steam, and the liquid oils obtained by the decanting can be subdivided into easily refinable lubricating oils and gas oils.

As a result of this manner of operation only a small amount of asphalt is precipitated together with the solid substances, whereas the main amount thereof which is free from solid substances, can either be sold or be utilized further in the process. Besides, the distillation of the valuable lubricating oils is not disturbed by the presence of considerable amounts of asphalt which are, easily subject to decomposition.

Now the example: 100 kg. of distillation residues having a temperature of over 280° C. and resulting from berginized pit-coal (softening point Krämer-Sandow 35°, with 25 % of undissoluble parts of coal and ashes) are mixed at a temperature of 200° C. with 20 kg. of raw petroleum, the residues being forcibly stirred while the admixing takes place. After about one hour 40 kg. of solid asphalt and undissoluble components will have been deposited upon the bottom of the mixing chamber. The oil present over the deposit or precipitate is then withdrawn. Within from 3 to 5 hours thereafter another amount of 40 kg. of soft asphalt free from undissoluble components separate and precipitate from said oil, and there remain 40 kg. of a thinly liquid, reddish-brown oil which is poor in asphalt. Finally, the precipitation means is re-gained from all three fractional precipitations by being blown off by means of steam.

The same procedure can be employed in connection with other asphalt-containing bituminous materials. It has not been known hitherto that relatively small quantities (such as about 20%) of aliphatic oils can be used for the separation of asphalt and other impurities.

In order to re-gain the oil used for the separation of precipitation the boiling limits of that oil may be so chosen that it can be easily

regained, when the solutions are worked down, by distillation.

I claim:

5. 1. The process of working down the products arising when coal is liquefied by hydrogenation, consisting in freeing the product obtained by the liquefaction of the coal from water and from components having a low boiling point, admixing an aliphatic hydrocarbon thereto, and separating the precipitated mixture of asphalt and solid, insoluble substances from the dissolved mixture of coal oil and precipitation oil, substantially as set forth. 55
10. 2. The process of working down the products arising when coal is liquefied by hydrogenation, consisting in freeing the product obtained by liquefaction of the coal from water and from components having a low boiling point, admixing gas oil thereto, and separating the precipitated mixture of asphalt and solid, insoluble substances from the dissolved mixture of coal oil and precipitation oil, substantially as set forth. 60
15. 3. The process of working down the products arising when coal is liquefied by hydrogenation, consisting in admixing an aliphatic hydrocarbon to the product obtained by the liquefaction of the coal and containing solid components and having been freed from water and components having a low boiling point, and separating the precipitated mixture of asphalt and solid, insoluble substances from the dissolved mixture of coal oil and precipitation oil, substantially as set forth. 65
20. 4. The process of working down the product obtained when coal is liquefied by hydrogenation, consisting in freeing the product obtained by the liquefaction of the coal from water and from components having a low boiling point, admixing an aliphatic hydrocarbon thereto, separating from said mixture at first only a small amount of asphalt together with the insoluble solid substances, allowing the remaining mixture to settle for an appropriate length of time, and separating another amount of asphalt, substantially as set forth. 70
25. 5. The process of working down the products arising when coal is liquefied by hydrogenation, consisting in admixing an aliphatic hydrocarbon thereto, separating from said mixture at first only a small amount of asphalt together with the insoluble solid substances, allowing the remaining mixture to settle for an appropriate length of time, and repeating the separation of the asphalt until the said products have been worked down. 75
30. 6. The process of working down the products arising when coal is liquefied by hydrogenation, consisting in freeing the product obtained by the liquefaction of the coal from water and from components having a low boiling point, admixing thereto an aliphatic hydrocarbon, the boiling point of which is such that it can be easily re-gained, while the solutions are worked down, by distillation; and separating the precipitated mixture of asphalt and solid, insoluble substances from the dissolved mixture of coal oil and precipitation oil, substantially as set forth. 80
35. 7. The process of working down the products arising when coal is liquefied by hydrogenation, consisting in admixing an aliphatic hydrocarbon thereto, separating from said mixture at first only a small amount of asphalt together with the insoluble solid substances, allowing the remaining mixture to settle for an appropriate length of time, and repeating the separation of the asphalt until the said products have been worked down. 85
40. 8. The process of working down the products arising when coal is liquefied by hydrogenation, consisting in freeing the product obtained by the liquefaction of the coal from water and from components having a low boiling point, admixing a relatively small amount of an aliphatic oil thereto, and separating the precipitated mixture of asphalt and solid, insoluble substances from the dissolved mixture of coal oil and precipitation oil, substantially as set forth. 90
45. 9. The process of working down the product obtained when coal is liquefied by hydrogenation, consisting in freeing the product

from water and from components having a low boiling point, admixing about 20% of an aliphatic oil thereto, and separating the precipitated mixture of asphalt and solid, insoluble substances from the dissolved mixture of coal oil and precipitation oil, substantially as set forth. 95

10. 6. The process of working down the products arising when coal is liquefied by hydrogenation, consisting in freeing the product obtained by the liquefaction of the coal from water and from components having a low boiling point, admixing an aliphatic hydrocarbon thereto, separating from said mixture at first only a small amount of asphalt together with the insoluble solid substances, allowing the remaining mixture to settle for an appropriate length of time, and separating another amount of asphalt, substantially as set forth. 65

11. 7. The process of working down the products arising when coal is liquefied by hydrogenation, consisting in admixing an aliphatic hydrocarbon thereto, separating from said mixture at first only a small amount of asphalt together with the insoluble solid substances, allowing the remaining mixture to settle for an appropriate length of time, and repeating the separation of the asphalt until the said products have been worked down. 70

12. 8. The process of working down the products arising when coal is liquefied by hydrogenation, consisting in freeing the product obtained by the liquefaction of the coal from water and from components having a low boiling point, admixing thereto an aliphatic hydrocarbon, the boiling point of which is such that it can be easily re-gained, while the solutions are worked down, by distillation; and separating the precipitated mixture of asphalt and solid, insoluble substances from the dissolved mixture of coal oil and precipitation oil, substantially as set forth. 95

In testimony whereof I affix my signature.

DR. KARL SCHOENEMANN.
